ABSTRACT

For use with a novel recutter screen having a cutter or cutters capable of being resharpened, a jig for holding the screen in proper relationship to the grinder which does the resharpening.

Fig. 2

Fig. 1

SHARPENING JIG FOR RECUTTER SCREEN

BACKGROUND AND SUMMARY OF THE
INVENTION

In my previous and co-pending application, Ser. No. 278,736, filed Aug. 8, 1972, I disclosed a novel type of recutter screen for a forage harvester. One of the chief features of that screen was the use of a resharpenable edge on the cutters so that the cutters can maintain their full efficiency for an extended period.

Because the screen is generally arcuate in transverse cross section, it is somewhat clumsy to handle if resharpening is to be done manually. Therefore, I have invented a jig for holding the screen and grinder in proper relationship for resharpening the cutting edge or edges on the screen.

FIGURES

FIG. 1 is a medial sectional view of my jig with a screen and grinder shown in place,

FIG. 2 is an end elevational view similar to FIG. 1 with the screen and grinder removed, and

FIG. 3 is a view from line 3—3 of FIG. 2.

DESCRIPTION

Briefly my device comprises a jig which is widely adjustable to hold a workpiece such as my recutter screen in proper position. The jig also supports a grinder in position to allow it to be swung across the face of the screen to engage the cutting edge at a proper angle to be resharpened.

More specifically and referring to the drawings, I mount my device on a base having feet 10 adapted to rest on a workbench. These feet support a longitudinal bar or tube 11 from a bracket or end member 12. An arm 13 is adjustably mounted on the bar 11 by means of a U-shaped bracket 14. This allows the arm 13 to be held in varying pivotal positions relative to the bar 11.

A rod 15 is adjustably fixed to the arm 13 by means of a bracket 16. The rod is, therefore, pivotally adjustable relative to the arm, and may also be further adjustable because of the provision of varying attachment points at any one series of holes 17 in the arm 13.

In my preferred embodiment, the rod 15 is rotatable within the bracket 16 and is screw threaded. Nut means 18 is threaded onto the rod and supports a carrier bracket 19. The rod 15 may be provided with a crank 20 which may be used to adjust the position of the nut 18 on the rod 15. The carrier 19 is adapted to hold one edge of the recutter screen 21 (FIG. 1). It will be apparent that by means of all the various adjustments, the edge can be positioned with a great deal of flexibility within a considerable range of locations.

The flange 23 of the screen is also held in a variable location. This is done by providing clamping means 24 on a lateral member 25. This member is fixed on arms 26 which are pivotally adjustable relative to the end members 12 or to extension 27 thereof. Thus, the flange edge of the recutter screen is also adjustably held relative to the base, although this adjustment is limited to the arcuate path defined by the pivoting of the arms 26.

10 The grinder 30 may be of the type in which the grinding wheel rotates on an axis at right angles to the axis of its driving motor and by which the grinder is usually hand-held. This grinder is also adjustably mounted. In order to accomplish this, I provide threaded rods 31 extending from the extensions 27. A longitudinal bar 32 having flattened ends 33 is mounted on these rods 31. Nuts threaded onto the rods 31 above and below the flattened end 33 of the bar 32 provide for adjustment of that bar toward or away from the screen 21.

20 A swinging bracket 35 adapted to hold the grinder 30 is mounted for free pivotal and sliding motion on the bar 32. This bracket also holds the grinder so that it can freely pivot on an axis parallel to the bar 32. By this type of mounting, the grinding wheel will be free to sweep across the face of the screen to grind the edge of the cutter.

25 It will be readily apparent that the jig is widely adjustable for varying sizes of screen, for varying location of cutter members on the screen, for varying curvatures of the screens, and for different makes or model of grinders.

I claim:

1. For holding a recutter screen having an arcuate body terminating in an edge on one end of the arc and a flange on the opposite end, a grinding jig comprising a base, flange holding means mounted on said base adapted to hold said flange, edge holding means on said base including an arm pivotally mounted on said base, rod means pivoted to said arm and threaded at one end, said rod being rotatable, clamp means threadably engaged with said rod and adapted to hold said edge of the screen whereby rotation of said rod results in adjustment of the edge, and grinder mounting means movably mounted from said base whereby a grinder can sweep across the face of said screen.

2. The device of claim 1 in which said grinder mounting means includes a longitudinal bar adjustably mounted on said base for movement toward and away from the concave part of said arcuate body, and means swingably mounted on said longitudinal bar adapted to hold a grinding device.
